W. M. WHITE,
DISPLAY RACK FOR GLOVES,
APPLICATION FILED MAR. 24, 1917.

1,253,320.

Patented Jan. 15, 1918.

UNITED STATES PATENT OFFICE.

WALTER MOTLEY WHITE, OF ROCKY MOUNT, VIRGINIA.

DISPLAY-RACK FOR GLOVES.

1,253,320.

Specification of Letters Patent. Patented Jan. 15, 1918.

Application filed March 24, 1917. Serial No. 157,170.

To all whom it may concern:

Be it known that I, WALTER M. WHITE, a citizen of the United States, residing at Rockymount, in the county of Franklin and State of Virginia, have invented a new and useful Display-Rack for Gloves, of which the following is a specification.

The present invention appertains generally to display racks, and aims to provide 10 a device of that character constructed especially for displaying gloves in an effective manner, and enabling a selection to be conveniently made without the unnecessary handling of the gloves.

This invention affords practical and efficacious means for holding and displaying various sizes, styles and prices of gloves or equivalent articles, to enhance the selection of the gloves, both by the salesman and customer, it being well known that the ordinary method of storing and handling gloves is open to a number of objections, as for example, the necessity for unnecessarily handling the gloves, the confusion attendant to the mixing of various sizes and styles of gloves, and the like.

It is also the object of the invention to provide a display rack having novel means for supporting the gloves, and to facilitate their selection and removal.

The invention has for another object the provision of a display rack of the nature indicated which is simple and inexpensive in construction, and which will be practical, serviceable and convenient in use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:

Figure 1 is a side elevation of the display rack, some of the supporting arms being removed for sake of clearness.

Fig. 2 is a top plan view.

Fig. 3 is a perspective view of one of the arms, portions being broken away.

Fig. 4 is a perspective view of one of the glove holding clasps.

Fig. 5 is a perspective view illustrating a modification of the tag holding means.

In carrying out the invention, there is provided a standard or post 1, preferably supported for rotation, such as by seating the lower end of the standard in a socket 2, which can be carried by a case forming the base of the display rack, and the drawer 4 can be provided in the case 3 for holding the clasps and other articles used in connection with a stand.

Carried by the standard 1 are a plurality of sets of radial arms. Thus, one set of arms can be provided for each style or price of glove, and a sufficient number of arms can be provided in each set for the various sizes of gloves of the particular style or price. With the structure as illustrated, three different styles or prices of gloves can be displayed 1, and a number of gloves of each size 75 of each style can be hung from one arm. The display rack can be seated on a counter in the store, or elsewhere, for effectively displaying gloves.

The arms, as illustrated, are telescopic or extensible, each embodying a radial tubular section 5 having its inner end secured to the standard 1 in any suitable manner, and slidably receiving an outer section or rod 6.

In order to hang a comparatively large 85 number of gloves of one size from each arm, there is provided a hanger, bent from wire or other suitable stock, and embodying an elongated horizontal member 7 disposed below the arm parallel therewith, and provided at its inner end with an upturned portion 8 provided with an eye or loop 8' slidably embracing the section 5 of the arm. The outer end of the member 7 has an upturned portion 9 provided with a coil 10 rigidly embracing the outer end of the section 6 of the arm, whereby the hanger is 95 movable with said section 6. The section 6 is normally slid inwardly within the section 5, thereby moving the hanger under the section 5, and bringing the gloves adjacent to the standard, and by pulling the section 6 and hanger outwardly, this moves the corresponding bunch of gloves outwardly from the rest to aid in the gloves being applied to and removed from the hanger.

The outer end of the arms are provided with tag holding means, whereby tags indicating the sizes, price, styles, and other information, can be applied to the ends of the 110

arms for convenience in making the selection. As illustrated in Fig. 3, the tag holding means is formed from the wire constituting the hanger.

5 Thus, from the coil 10, the wire is extended toward one side, as at 11, and is then extended upwardly and bent back to provide a loop 12. From the loop 12, the wire is bent, as at 13, to extend across the rod or 10 section 6 to the opposite side, and from the portion 13, the wire is bent upwardly and doubled to provide an upstanding loop 14 opposite to the loop 12. The loops 12 and 14 thus provide a receptacle for a tag 15, and 15 the upper portions or bends of the loops can be curved slightly away from one another to receive the tag.

A modified form of tag holding means is illustrated in Fig. 5, the same embodying an 20 upright sheet metal member 13' having bent back flanges 14' at its side edges for receiving the tag in front of the plate 13'. This plate can be secured upon the section 6 near its free end in any suitable manner, such 25 as by extending a finger 12' upwardly from the coil 10 to which the plate 13' can be soldered or otherwise secured.

In figure 4, there is illustrated one of the 30 clasps which are used for applying the gloves to the hangers. This clasp has the

pivoted levers 16 provided with the transversely elongated jaws 17 for gripping the end of the glove in a flat condition, without injuring it, and one of the levers 16 is extended into a hook 18 to engage over the 35 member 7 of the hanger for suspending the glove therefrom. The clasps can be contained within the drawer 4 when not in use, and are applied to the gloves before they are hung from the arms, the clasps being 40 removed from the gloves as they are sold, and returned to the drawer.

Having thus described the invention, what is claimed as new is:—

A display rack embodying an arm having 45 a tubular section and a rod slidable therein, an elongated hanger below said arm having upturned portions at its ends, one upturned portion having an eye slideable on said tubular section, and the other upturned portion 50 having a coil tightly embracing the rod and a tag holding portion projecting from said coil.

In testimony that I claim the foregoing as my own, I have hereto affixed my signature 55 in the presence of two witnesses.

WALTER MOTLEY WHITE.
